UNITED STATES PATENT OFFICE.

WALTER A. SPEAR, OF DAYTON, OHIO, ASSIGNOR TO THE JOYCE-CRIDLAND COMPANY, OF DAYTON, OHIO, A CORPORATION OF OHIO.

SELF-LOWERING LIFTING JACK.

Application filed January 12, 1924. Serial No. 685,725.

To all whom it may concern:

Be it known that I, WALTER A. SPEAR, a citizen of the United States, residing at Dayton, in the county of Montgomery and State of Ohio, have invented certain new and useful Improvements in Self-Lowering Lifting Jacks, of which the following is a specification, reference being had therein to the accompanying drawing.

10 This invention relates to self-lowering lifting jacks.

One object of the invention is to provide a simple efficient mechanism for controlling the lowering of the load; and to provide such a mechanism which will be compact in arrangement, of a strong durable character and which can be produced at a relatively low cost.

20 Other objects of the invention will appear as the mechanism is described in detail.

In the accompanying drawings Fig. 1 is a side elevation, partly broken away, of a jack embodying my invention; Fig. 2 is a front elevation of such a jack, partly broken away and partly in section; Fig. 3 is a sectional view of the lowering mechanism; Fig. 4 is an end elevation of the lowering mechanism with the end wall of the housing removed; and Fig. 5 is a detail view of the locking pawl.

25 In these drawings I have illustrated one embodiment of my invention and have shown the same as applied to a lifting jack of a well known type, but it will be understood that the lowering mechanism may take various forms and may be applied to jacks of various kinds without departing from the spirit of the invention.

30 In the form here shown the jack comprises a hollow standard 1 having at its lower end a base portion 2 by means of which it is supported normally in an upright position. Mounted in the upper portion of the standard and held against rotation relatively thereto is a nut 3 in which is mounted a screw threaded lifting element 4 having at its upper end a lifting head 5 adapted to engage the work or load to be lifted. Secured to the lifting head 5 and depending therefrom is a housing 6 the lower portion of which is cylindrical and is slidably mounted on the standard 1. Rigidly secured to the lifting element 4 is a beveled gear 7 with which meshes a second beveled gear 8 which is rigidly secured to a

shaft 9 journaled in suitable bearings carried by the housing 6. In the present instance, the shaft is journaled in bearings 10 and 11 formed in a supplemental housing 12 which is rigidly secured to the main housing 6 but has no communication therewith, thus enabling the supplemental housing to contain a lubricant for the mechanism which is mounted therein. The outer end of the shaft 9 projects beyond the supplemental housing 12 and has rigidly secured thereto a ratchet wheel 13. A lever 14 is rotatably mounted on the end of the shaft 9 and carries a pawl 15 which cooperates with the ratchet wheel 13 to rotate the shaft 9 and thereby elevate the lifting element 4. I have here shown only the lever socket but it will be understood that a spike or bar is removably mounted in this socket for actuating the lifting element.

50 The lifting element 4 has a high pitch thread and is otherwise so arranged that, when unrestrained, it will move downwardly under the weight of the load. A shaft is so connected with the lifting element that it will be rotated by the downward movement thereof and a retarding device or brake is provided for controlling the speed of rotation of the shaft. This device preferably consists of two parts; one of which is rotated by the shaft and one of which is held against rotation and in order to impart to the first mentioned part of the retarding device a speed which is sufficiently high to enable the proper control to be had, I have interposed 55 planetary gearing between the same and the shaft. In the present instance, I have utilized the shaft 9, by means of which the lifting element is elevated, for controlling the lowering movement of the lifting element. An annular gear 16 is mounted within the supplemental housing 12 concentric with the axis of the shaft 9 and is rigidly secured to the inner wall of the supplemental housing. A second gear 17 is rotatably mounted on the shaft 9 and, in the present instance, is provided with an elongated hub 18. This second gear is arranged adjacent to the first mentioned gear and is provided with less teeth than the first mentioned gear. However, in the present construction, the two gears are of approximately the same diameter. It will be noted that the second gear 17, being rotatably mounted on the shaft, may be held against rotation there- 60 65 70 75 80 85 90 95 100 105 110

2

with during the lifting operation, and means are provided for connecting this gear with the shaft so that it will rotate therewith when the lifting element moves downwardly, 5 that is, when the shaft 9 rotates in a reverse direction. As here shown, this means comprises a clutch member 19 rigidly secured to the gear 17. A second clutch member 20 is slidably mounted on the shaft for movement 10 into and out of cooperative engagement with the clutch member 19 and is held against rotation relatively to the shaft. The second clutch member 20 is yieldably pressed into engagement with the clutch member 19 and 15 the two clutch members are provided with ratchet teeth so arranged that when the clutch member 20 rotates with the shaft during the elevation of the lifting element its teeth will ride over the teeth of the other 20 clutch member 19 and when the shaft rotates in a reverse direction the teeth of the clutch member 20 will operatively engage the teeth of the clutch member 19. Any suitable means may be provided for pressing the 25 clutch member 20 toward the clutch member 19 but I preferably employ a series of springs, one of which is shown at 21, which act upon the clutch member 20 through balls 22 which serve to lessen the frictional contact between the parts. Rotatably mounted upon the hub 18 of the gear 17 is a supporting member 23 which carries a plurality of pinions 24 which extend across the peripheries of and mesh with the teeth of both 30 gears, 16 and 17. In the present construction these pinions are rotatably mounted upon pins or studs 25 which are rigidly mounted in the supporting member 23, this member being here shown as a disk and 35 being rotatable independently of the gear 17. It will be apparent, therefore, that when the shaft 9 is rotated in a reverse direction the clutch 20 will pick up the clutch 19 and cause the gear 17 to be rotated with the shaft. The rotation of the gear 17 also rotates the planetary pinions 24 and, inasmuch as the gear 16 is held against rotation, these 40 planetary pinions are caused to travel about the gear 16 and they carry with them the supporting member 23. The ratio of the gear 16 to the gear 17 is such that the supporting member 23 will be rotated at a relatively high speed. A suitable device is provided to resist the rotation of the supporting 45 member 23, thereby enabling the speed at which the load is lowered to be controlled. This device, which in effect constitutes a brake, may be of any suitable character and, as here shown, is in the form of a friction 50 clutch comprising a clutch member 26 which is slidably mounted on the elongated hub 18 of the gear 17 and has a friction face adapted to engage a corresponding friction surface or face 27 on the supporting member 55 or disk 23. The clutch member 26 is held

against rotation with the hub 18 and, in the present instance, is provided in its opposite sides with recesses 28 into which extend pins 29 carried by a yoke 30. This yoke is pivotally mounted in the upper portion of the 70 supplemental housing on an axis transverse to the shaft 9 and the pins 29 serve not only to hold the clutch member 26 against rotation but also to move the same toward or from the cooperating friction surface on the 75 supporting member 23. Springs 31 act on the clutch member 26 to normally press the same toward the supporting member 23. Means are provided under the control of the operator for actuating the yoke 30 to move 80 the clutch into its inoperative position. As here shown, the yoke 30 has a downwardly extending arm 32 which is arranged to be engaged by a finger 33 rigidly secured to a short shaft 34 mounted in the wall of the 85 supplemental housing and having secured to its outer end a short lever 35 by means of which it may be actuated. The arrangement of the finger 33 with relation to the arm 32 on the yoke is such that when the 90 lever 35 is moved in one direction the finger will engage the arm of the yoke and move the yoke outwardly so as to move the clutch member 26 into an inoperative position. The clutch member being spring pressed 95 against the cooperating clutch member or supporting member 23 it will be obvious that the frictional contact between the two members may be varied by the manipulation of the lever 35 so as to allow the load to be 100 lowered at the desired speed. When the lever 35 is released the clutch members are automatically moved into full engagement, in which positions they will have sufficient frictional contact to completely check the 105 movement of the load. I have also provided means for positively locking the controlling mechanism against slipping after the load has been stopped in the desired position. To this end the supporting member 23 has 110 formed on that face thereof adjacent to the yoke 30 a series of ratchet teeth 36 and the lever operated finger 33 is in the form of a pawl adapted to engage the ratchet teeth 36. A spring 37 is interposed between the finger 115 or pawl 33 and the arm 32 of the yoke so that the pawl will be moved into engagement with the ratchet teeth when the lever 35 is released. However, in order to prevent this pawl from engaging the ratchet teeth 120 before the controlling device has completely checked the movement of the load I prefer to provide some means for retarding or delaying the action of the pawl. Of course, the spring 37 might be omitted and the pawl moved into engagement with the ratchet teeth by the manipulation of the lever 35 125 after the movement of the load has been checked. It is desirable, however, that the pawl automatically engage the ratchet teeth 130

and I have therefore provided the same with a retarding device in the form of a dash pot 38 in which is mounted a piston 39, the rod 40 of which is connected by means of a link 41 with a finger 42 secured to the finger or pawl 33. The dash pot is provided with an inlet port 43 controlled by a check valve 44 which permits the entrance of air to enable the quick movement of the piston 39 when the pawl 33 is moved to its inoperative position. When the piston moves in the opposite direction and the pawl moves toward the ratchet teeth the check valve 44 closes and the air escapes through a restricted port 45 which so retards the movement of the piston, and consequently of the pawl 33, as to allow ample time for the brake or friction clutch to check the movement of the load before the pawl engages the ratchet teeth.

The operation of the device will be readily understood from the foregoing description and it will be apparent that I have provided controlling mechanism for a self-lowering jack which while very simple in its construction is highly efficient in its operation and will enable the downward movement of the load to be absolutely controlled by the operator. The construction is of a very strong durable character but is such that it can be produced at a relatively low cost and, further, is of such a character that the parts are not liable to be disarranged or broken in operation.

While I have shown and described one embodiment of my invention I wish it to be understood that I do not desire to be limited to the details thereof as various modifications may appear to a person skilled in the art.

Having now fully described my invention, what I claim as new and desire to secure by Letters Patent, is:

1. In a lifting jack, a standard, a lifting element supported by said standard, a shaft connected with said lifting element for rotation thereby when said lifting element is moved downwardly, a device to resist the rotation of said shaft by said lifting element, and planetary gearing interposed between said device and said shaft.

2. In a lifting jack, a standard, a lifting element supported by said standard, a shaft connected with said lifting element for rotation thereby when said lifting element is moved downwardly, a device to resist the rotation of said shaft by said lifting element, said device comprising two parts, planetary gearing interposed between one of said parts and said shaft, and means for moving the other part of said device into and out of cooperative relation with the first mentioned part thereof.

3. In a lifting jack, a standard, a lifting element supported by said standard, a shaft connected with said lifting element for rotation

thereby when said lifting element is moved downwardly, a device to resist the rotation of said shaft by said lifting element, planetary gearing operatively connected with said shaft, a friction member connected with said planetary gearing, a second friction member, means for yieldably pressing said friction member into contact with the first mentioned friction member, and means for retracting said second friction member.

4. In a lifting jack, a standard, a lifting element supported by said standard, a shaft connected with said lifting element for rotation thereby when said lifting element is moved downwardly, a device to resist the rotation of said shaft by said lifting element, planetary gearing interposed between said device and said shaft, and a clutch to connect said planetary gearing with said shaft.

5. In a lifting jack, a standard, a lifting element supported by said standard, a shaft connected with said lifting element for rotation thereby when said lifting element moves downwardly, a pair of gears mounted about said shaft, one of said gears being fixed against rotation and the other being connected with said shaft for rotation therewith, a supporting member rotatable about the axis of said shaft, pinions carried by said supporting member and meshing with both of said gears, a friction device cooperating with said supporting member to resist the rotation of said shaft, and means for manipulating said friction device.

6. In a lifting jack, a standard, a lifting element supported by said standard, a shaft connected with said lifting element for rotation thereby when said lifting element moves downwardly, a pair of gears mounted about said shaft, one of said gears being fixed against rotation and the other being connected with said shaft for rotation therewith, a supporting member rotatable about the axis of said shaft, pinions carried by said supporting member and meshing with both of said gears, said supporting member having a friction surface, a friction member mounted for movement into and out of contact with the friction surface of said supporting member and held against rotation, and means for actuating said friction member.

7. In a lifting jack, a standard, a lifting element supported by said standard, a shaft connected with said lifting element for rotation thereby when said lifting element moves downwardly, a pair of gears mounted about said shaft, one of said gears being fixed against rotation and the other being connected with said shaft for rotation therewith, a supporting member rotatable about the axis of said shaft, pinions carried by said supporting member and meshing with both of said gears, said supporting member hav-

ing a friction surface, a friction member mounted for movement into and out of contact with the friction surface of said supporting member and held against rotation, 5 an actuating member connected with said friction member, a lever, and means actuated by said lever to impart movement to said actuating member.

8. In a lifting jack, a standard, a lifting 10 element supported by said standard, a shaft connected with said lifting element for rotation thereby when said lifting element moves downwardly, a pair of gears mounted about said shaft, one of said gears being fixed 15 against rotation and the other being connected with said shaft for rotation therewith, a supporting member rotatable about the axis of said shaft, pinions carried by said supporting member and meshing with both 20 of said gears, said supporting member having a friction surface, a friction member mounted for movement into and out of contact with the friction surface of said supporting member and held against rotation, 25 springs to move said friction member toward said supporting member, a pivoted actuating device operatively connected with said friction member, a finger adapted to engage said actuating device to operate the same, and 30 means for actuating said finger.

9. In a lifting jack, a standard, a lifting element supported by said standard, a shaft connected with said lifting element for rotation thereby when said lifting element 35 moves downwardly, a pair of gears mounted about said shaft, one of said gears being fixed against rotation and the other being connected with said shaft for rotation therewith, a supporting member rotatable 40 about the axis of said shaft, pinions carried by said supporting member and meshing with both of said gears, said supporting member having a friction surface, a friction member mounted for movement into and 45 out of contact with the friction surface of said supporting member and held against rotation, springs to move said friction member toward said supporting member, a pivoted actuating device operatively connected 50 with said friction member, a finger adapted to engage said actuating device to operate the same, and means for actuating said finger, said supporting member having teeth and said finger being arranged to engage 55 said teeth to lock said supporting member against rotation.

10. In a lifting jack, a standard, a lifting element supported by said standard, a shaft connected with said lifting element for rotation thereby when said lifting element 60 moves downwardly, a pair of gears mounted about said shaft, one of said gears being fixed against rotation and the other being connected with said shaft for rotation 65 therewith, a supporting member rotatable

about the axis of said shaft, pinions carried by said supporting member and meshing with both of said gears, said supporting member having a friction surface, a friction member mounted for movement into and 70 out of contact with the friction surface of said supporting member and held against rotation, means for actuating said friction member, a device other than said friction member to lock said supporting member 75 against rotation, and means for first retracting said locking device and then imparting movement to said actuating device to withdraw said friction member.

11. In a lifting jack, a standard, a lifting 80 element supported by said standard, a shaft connected with said lifting element for rotation thereby when said lifting element moves downwardly, a pair of gears mounted about said shaft, one of said gears being 85 fixed against rotation and the other being connected with said shaft for rotation therewith, a supporting member rotatable about the axis of said shaft, pinions carried by said supporting member and meshing with both of said gears, said supporting member having a friction surface, a friction member mounted for movement into and 90 out of contact with the friction surface of said supporting member and held against 95 rotation, means for actuating said friction member, a locking member to engage said supporting member and hold the same against rotation, said locking member being so arranged that when moved into its inoperative position it will engage said actuating device and retract said friction member, and means for actuating said locking member.

12. In a lifting jack, a standard, a lifting 100 element supported by said standard, a shaft connected with said lifting element for rotation thereby when said lifting element moves downwardly, a pair of gears mounted about said shaft, one of said gears being 105 fixed against rotation and the other being connected with said shaft for rotation therewith, a supporting member rotatable about the axis of said shaft, pinions carried by said supporting member and meshing with both of said gears, said supporting member having a friction surface, a friction member mounted for movement into and 110 out of contact with the friction surface of said supporting member and held against 115 rotation, means for actuating said friction member, a locking member to engage said supporting member and hold the same against rotation, said locking member being so arranged that when moved into its inoperative position it will engage said actuating device and retract said friction member, means for actuating said locking member, a spring interposed between said locking member and said actuating device, 120 125 130

- and means to retard the action of said locking device by said spring, thereby enabling said friction member to operatively engage said supporting member before the latter is engaged by said locking member. 5
13. In a lifting jack, a standard, a lifting element supported by said standard, means comprising a shaft for actuating said lifting element, a pair of gears mounted about said shaft, one of said gears being rigidly secured to a fixed support and the other of said gears being rotatable relatively to said shaft, a supporting member rotatable about the axis of said shaft, pinions carried by said supporting member, each meshing with both of said gears, means for connecting said rotatable gear with said shaft when said lifting element moves downwardly, and means to control the movement of said supporting member. 10
14. In a lifting jack, a standard, a lifting element supported by said standard, means comprising a shaft for actuating said lifting element, a pair of gears mounted about said shaft, one of said gears being rigidly secured to a fixed support, a clutch to connect the other of said gears with said shaft when said lifting element is moved downwardly, a supporting member rotatable about the axis of said shaft, a plurality of pinions carried by said supporting member and each meshing with both of said gears, said supporting member having a friction surface, a friction member mounted about said shaft for movement into and out of contact with the friction surface of said supporting member and held against rotation, a yoke pivotally mounted within said housing and operatively connected with said friction member, a shaft journaled in said housing, a part carried by said last mentioned shaft and arranged to actuate said yoke, and a finger piece arranged exteriorly of said housing and secured to said last mentioned shaft. 15
15. In a lifting jack, a standard, a lifting element supported by said standard, means comprising a shaft for actuating said lifting element, a housing having bearings for said shaft, a pair of gears mounted about said shaft, one of said gears being rigidly secured to said housing, a clutch to connect the other of said gears with said shaft, a supporting member rotatable about the axis of said shaft, a plurality of pinions carried by said supporting member and each meshing with both of said gears, said supporting member having a friction surface, a friction member mounted about said shaft for movement into and out of contact with the friction surface of said supporting member and held against rotation, a yoke pivotally mounted within said housing and operatively connected with said friction member, a shaft journaled in said housing, a part carried by said last mentioned shaft and arranged to actuate said yoke, and a finger piece arranged exteriorly of said housing and secured to said last mentioned shaft. 20
16. In a lifting jack, a standard, a lifting element supported by said standard, means comprising a shaft for actuating said lifting element, a housing having bearings for said shaft, a pair of gears mounted about said shaft, one of said gears being rigidly secured to said housing, a clutch to connect the other of said gears with said shaft, a supporting member rotatable about the axis of said shaft, a plurality of pinions carried by said supporting member and each meshing with both of said gears, said supporting member having a friction surface, a friction member mounted about said shaft for movement into and out of contact with the friction surface of said supporting member and held against rotation, a yoke pivotally mounted within said housing and operatively connected with said friction member, a shaft journaled in said housing, a part carried by said last mentioned shaft and arranged to actuate said yoke, and a finger piece arranged exteriorly of said housing and secured to said last mentioned shaft. 25
17. In a lifting jack, a standard, a lifting element supported by said standard, means comprising a shaft for actuating said lifting element, a housing having bearings for said shaft, a pair of gears mounted about said shaft, one of said gears being rigidly secured to said housing, a clutch to connect the other of said gears with said shaft, a supporting member rotatable about the axis of said shaft, a plurality of pinions carried by said supporting member and each meshing with both of said gears, said supporting member having a friction surface, a friction member mounted about said shaft for movement into and out of contact with the friction surface of said supporting member and held against rotation, a yoke pivotally mounted within said housing and operatively connected with said friction member, a shaft journaled in said housing, a part carried by said last mentioned shaft and arranged to actuate said yoke, and a finger piece arranged exteriorly of said housing and secured to said last mentioned shaft. 30
18. In a lifting jack, a standard, a lifting element supported by said standard, a shaft connected with said lifting element for rotation thereby when said lifting element is moved downward, a retarding device for said shaft comprising a member connected with said shaft for rotation thereby when said shaft is rotated by the downward movement of said lifting element, a second member held against rotation and movable into and out of engagement with the first mentioned member, an actuating device for said second member, means to lock the first mentioned member against rotation, and means for moving said locking means into an inoperative position and causing the same to impart movement to said actuating device. 35
19. In a lifting jack, a standard, a lifting element supported by said standard, a shaft connected with said lifting element for rotation thereby when said lifting element is moved downward, a retarding device for said shaft comprising a member connected with said shaft for rotation thereby when

said shaft is rotated by the downward movement of said lifting element, a second member held against rotation and movable into and out of engagement with the first mentioned member, an actuating device for said second member, means to lock the first mentioned member against rotation, and means to actuate said locking means, said locking

means being so arranged that when moved into an inoperative position it will engage ¹⁰ said actuating device and move said second member of said retarding device into an inoperative position.

In testimony whereof I affix my signature hereto.

WALTER A. SPEAR.
